UNITED STATES PATENT OFFICE

JOHN B. FREYSINGER, OF NEW BRITAIN, CONNECTICUT, ASSIGNOR TO NORTH & JUDD MANUFACTURING COMPANY, OF NEW BRITAIN, CONNECTICUT, A CORPORATION OF CONNECTICUT

SEPARABLE FASTENER

Application filed March 19, 1932. Serial No. 599,871.

The present invention relates to separable fasteners, and has for an object the provision of an improved device of this kind which may be conveniently used in connecting two members or parts of the same member together.

The present invention may be used in connection with belts, wearing apparel, baggage, such as brief bags, et cetera.

A further object of the present invention is to provide a simple, strong, durable and inexpensive fastening device which may be quickly and easily operated.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein is shown, for illustrative purposes, one of the embodiments which the present invention may take,

Fig. 1 is a front view of a fastening device constructed in accordance with the present invention;

Fig. 2 is a view taken on the line 2—2 of Fig. 1 and looking in the direction of the arrows;

Fig. 3 is an end view of the catch member;

Fig. 4 is a view on the line 4—4 of Fig. 3 and looking in the direction of the arrows; and

Fig. 5 is a side elevation of a fastening device constructed according to the present invention.

Referring more particularly to the drawing, A designates, generally, a bar member, and B designates generally a catch member of the fastening device. The bar member may be formed from a piece or strip of sheet metal and has a base 10 which is formed by bending the strip of metal over upon itself from its opposite outer edges to provide the folds 11. The portions adjacent the sides of the strip of metal are then extended in contact-

ing relation, as at 12, for a short distance in a direction substantially at right angles to the base 10, and the free ends of the side portions are bent to provide the oppositely extending flanges 13 and 14 which lie in a plane substantially parallel to the plane of the base 10. The outer edge of the flange 14 is provided with a series of teeth 15 each of which has a squared end or abutment and an inclined side edge. While the bar member 60 is here shown as being straight, it obviously may be longitudinally curved. The forward ends of the flanges are bevelled or rounded, as at 9, so as to facilitate assembly of the two members. At the other end of the bar member A, and preferably formed integrally therewith, is a transversely extending loop 16 which affords means for securing the bar member to the element X which may be one end of a strap or belt, et cetera. The end of the element X may be threaded through the loop 16, folded back upon itself, and then secured by the rivet 17. The loop 16 is provided with a pair of upstanding ears 18 having roughened outer surfaces 19 adapted to be engaged by the thumb and forefinger of the user of the device. The connection between the bar A and the loop 16 is outwardly bent as at 20 so that the loop is disposed in substantially the same plane as the flanges 13 and 14, whereby the end of the element X will be disposed outwardly of the other end of the element when the device is in locked position.

The catch member B of the fastening device includes a frame member generally designated 21 and having a rear or base wall 22 provided at its ends with apertured ears 23 by means of which it may be secured to the other element Y which may be the end of a belt or the body of a brief bag, et cetera. The base 22 has, extending forwardly from each of its side edges, a wall 24, and from the forward side edges of each of the walls 24, extend the inwardly directed flanges 25 which partially overhang and are substantially parallel to the base 22.

Extending forwardly from the inner side edge of each flange 24 is a wall 26 substantially perpendicular to the base 22 but spaced

inwardly from the side edges thereof. These walls 26 support an outer or front wall 27 substantially parallel to, but of less width than, the base 22.

5 Pivoted to the front wall 27, as by the pivot pin 28, is a catch generally designated 29. The catch 29 comprises a plate 30 pivoted to and overlying the wall 27 of the frame member 21. The sides of the plate 30 taper 10 towards its right-hand end, that is, the end adjacent the pivot 28, and are provided with rearwardly extending flanges 31 and 32. The flange 31 is provided with a heel 33 which overhangs the right-hand end of the adjacent wall 26 of the frame member 21 and is 15 adapted to abut against the flange 13 of the bar member to limit the movement of the catch in one direction.

The flange 32 is provided at the left-hand 20 end thereof with a detent 34 which cooperates with the series of teeth 15 on the bar member A. The detent 34 is normally urged into its teeth engaging position by means of a V-shaped spring 35 confined between the flange 25 31 of the catch 29 and the adjacent wall 26 of the frame member 21. The spring 35 is restrained from longitudinal movement by an overhanging lip 36 on the flange 31, which lip 30 engages the free end of one of the legs of the spring. The taper of the flange 31 towards the wall 26 of the frame member 21 35 prevents the escape of the spring in the other direction. The movement of the catch, due to the influence of the spring, is limited by the engagement of the flange 32 of the catch against the adjacent wall 26 of the guide member, while movement of the catch in the opposite direction is further restricted by the opposite wall 26 of the frame member 21.

40 When it is desired to assemble the catch member and the bar member of the fastener, it is merely necessary for the user to grip the ears 18 of the bar member A between his thumb and finger and thread the bar member 45 through the catch member. The detent 34 will ratchet over the teeth 15 until the desired position is reached, when the detent 34 will engage behind the adjacent tooth 15 and lock the parts together. To separate the parts of 50 the fastener, the user presses his thumb or finger against the flange 31 of the catch 29 and swings the catch on its pivot 28 against the tension of the spring 35 to disengage the detent 34 from the teeth 15. The bar member 55 may then be removed from the catch member.

As many changes could be made in the above construction and many apparently 60 widely different embodiments of this invention could be made without departing from the scope thereof, it is intended that all matter contained in the above description or shown in the accompanying drawing shall be interpreted as illustrative and not in a 65 limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a separable fastener, a bar member having a track portion provided with a series of teeth on one of its outer edges, a catch member comprising a frame embracing said track portion and adapted to slide longitudinally relative thereto, and a catch pivoted to the frame in such a manner as to have swinging movement in a plane parallel to said track portion, said catch having at its free end and beyond the end of said frame a detent cooperating with the teeth of said track portion. 75

2. In a separable fastener, a bar member having a track portion provided with a series of teeth on one of its side edges, a catch member comprising a frame embracing said track portion and adapted to slide longitudinally thereof, a catch located externally of said frame and pivoted to the front wall thereof in such a manner as to have swinging movement in a plane parallel to said front wall and in a plane parallel with the track portion, said catch having a detent at one end located 85 beyond said frame and adapted to cooperate with said teeth, and a spring interposed between said frame and catch and normally urging the latter in a direction to engage its detent with said teeth. 90

3. In a separable fastener, a bar member having a track portion provided with a series of teeth on one of its side edges, a catch member having a frame embracing said track portion and having a front wall and a pair of side walls straddling said track portion, a catch overlying said front wall and pivoted thereto and having side flanges straddling said frame, one of said flanges having at one end an inturned detent adapted to cooperate with said teeth, and a spring between said frame and the other of said flanges. 100

4. In a separable fastener, a bar member having a base, a pair of flanges spaced from and substantially parallel to the base, one of the flanges having a series of teeth on its outer edge, a frame encircling said bar member and having a base portion receiving the base of the bar member and an outer portion of reduced width receiving said flanges, a catch pivoted to the front wall of said frame and having flanges at its opposite sides, said flanges straddling the reduced portion of the frame, one of said flanges having a detent at one end adapted to cooperate with said series of teeth, and a spring interposed between the other of said flanges and the adjacent side of said reduced portion of the frame. 115

5. In a separable fastener, a bar member having a base and a pair of flanges spaced from and substantially parallel to said base, 120

one of said flanges having a series of teeth on its outer edge, a catch member comprising a frame having a base portion receiving the base of said bar member in its longitudinal movement and having an outer portion receiving said flanges, and a catch pivoted to said frame and cooperating with said teeth.

6. In a separable fastener, a bar member having a base and a pair of flanges spaced from and substantially parallel to said base, one of said flanges having a series of teeth on its outer edge, a catch member including a frame having a base, a pair of spaced substantially parallel walls extending from the base of said frame, and a pair of inturned flanges carried by said walls and substantially parallel to the base of the frame, said frame also having a pair of spaced and substantially parallel walls carried by the flanges of said frame and a top wall supported by said last mentioned walls, and a spring pressed catch pivoted to said top wall and cooperating with said teeth.

7. In a separable fastener, a bar member having a track portion provided with a series of teeth on one of its outer edges, a catch member comprising a frame embracing said track portion and adapted to slide longitudinally relative thereto, and a catch pivoted to the frame and having at its free end and beyond the end of said frame a detent cooperating with the teeth of said track portion.

JOHN B. FREYSINGER.
